UNITED STATES PATENT OFFICE.

GEORGE H. RICHARDS, OF TERRE HAUTE, INDIANA.

AUTOMATIC CAR-STOP.

No. 874,349.

Specification of Letters Patent.

Patented Dec. 17, 1907.

Application filed July 26, 1907. Serial No. 385,607.

To all whom it may concern:

Be it known that I, GEORGE H. RICHARDS, a citizen of the United States, residing at Terre Haute, in the county of Vigo and State of Indiana, have invented certain new and useful Improvements in Automatic Car-Stops, of which the following is a specification.

My invention relates to devices for automatically arresting the progress of a car, by means located exterior to the car and actuated by an element separated therefrom; and my device is particularly applicable to use in mining operations, and tunnel excavation.

The principal objects of my invention, in its illustrated application to mining, are to provide improved means which will automatically prevent a car from running to the end of its track and there falling into a pit or well, termed a "sump", when the cage which carries the car to the surface is not at the end of the track in proper position to receive the car; to provide for the actuation of my device by the cage, so that when the latter is in proper receiving position at the end of the track, the car arresting means will have been actuated to leave the track unobstructed in order that a car can then run down upon the floor of the cage.

In the following description and claims, and in the accompanying drawing, I have indicated a preferred embodiment of my invention for accomplishing the foregoing and hereinafter indicated objects. It is however obvious that modifications, in the details of this embodiment, can be made without departing from the spirit and scope of my invention, and I therefore do not wish to be limited to the precise details indicated.

In the accompanying drawing—Figure 1 is an elevation of an application of my invention, showing in full lines, a car temporarily held by my device against further movement towards the "sump", and showing also, in dotted lines, the hoisting cage in its car-receiving position, after releasing the car, which is shown in dotted lines resting partially on the cage. Fig. 2 is a plan view of the car-stopping means, together with a portion of the track. Fig. 3 is a transverse section, showing, in full lines, my device holding a car against movement; and showing also, in dotted lines, the cage at rest in its car-receiving position, and the consequent position

of the car-stopping means. Fig. 4 is a perspective detail showing the car-stopping means. Figs. 5 and 6 are respectively longitudinal and transverse sections of a slightly modified form of a combined trip and resetting weight, the cage in each of these views being shown in its lowermost position ready to receive a car from the track.

1 indicates the rails of a tunnel track, 2 its ties, 3 a car adapted to run on the track, 4 the line of the "sump" at the end of the track, 5 the floor of the cage by means of which loaded cars are hoisted to the surface, 6 a portion of the under-framing of the cage, and 7 a fixed rest or seat, located in the "sump", and adapted to limit the downward movement of the cage and to support it in a position to receive or unload a car.

A rock-shaft 8 is preferably journaled in suitable bearings 9, secured to the ties adjacent a rail 1. This shaft is preferably provided with collars 10, which are preferably shrunk or forged on the shaft, but which, if desired, may be removably secured to the shaft. The collars are so located relative to the bearings that the shaft 8 will be prevented from material longitudinal movement therein.

The shaft 8 adjacent one end is preferably bent as at 11 to form an angular projection or knee; and the other end of the shaft, the end projecting into the "sump", carries a member 12 which forms, in one piece preferably, a trip and resetting weight for the shaft. The portion of the member 12, referring now to the first four figures of the drawing, projecting above the shaft 8, is preferably curved as at 13, and the portion 14 below the shaft is formed to constitute a weight sufficiently heavy, so that when carried from its normal vertical position, it will turn the shaft 8 in regaining such vertical position.

In some types of mine and tunnel construction, the floor 5 of the hoisting cage, as shown in Figs. 1 and 3, does not carry rails to receive the car wheels, which in this construction, run from the rails of the tunnel track upon the floor 5 of the cage, the flange of the car wheel running, if desired, upon one leg of an angle iron 15 secured to the floor of the cage. In this form of construction, the cage will not be required to descend as low, to receive a car, as it would were there rails on the floor of the cage: therefore the proper

elevation, of the combined trip and weight for this construction, can be secured by inclining the shaft as shown in Fig. 1, it being evident that the shaft could instead be positioned approximately horizontal at the required elevation for the trip and weight.

Figs. 5 and 6 show a type of construction, in which the cage floor 5 has secured thereto rails 16, upon which the cars 3 roll from the rails 1 of the tunnel track. This construction requires that the elevation of the cage floor, when in position to receive a car from the tunnel tracks, shall be lower than in the construction illustrated in Figs. 1 and 3. To meet this requirement, the member 12 is of the form shown in Figs. 5 and 6, wherein the weight portion, indicated at 17, has formed, preferably integral, therewith, an angularly disposed arm 18, having an outstanding 20 stud 19.

As the member 12 can be formed with its arm 18 of varying lengths, variations in the receiving position of the cage to meet different constructions, can be thus accommodated.

The operation of my device is as follows: When the cage 6 is not resting on its seat 7, but is in the vertical shaft of the tunnel, the member 12, through the influence of its weight portion, assumes the position shown in Figs. 1, 2 and 4, and also in full lines in Fig. 3; and in assuming this position, the member 12 turns the shaft 8 so that its knee projects inwardly over the adjacent rail 1, 35 and into the path of a car wheel thereon. If now a car move towards the "sump", the knee 11 will be struck by the alining front wheel of the car 3. This results in arresting the further progress of the car towards the 40 "sump", the car being thus held as long as the member 12 is not turned from its normal position. If the cage now descend, the under surface of its floor 5, comes in contact with the curved end 13 of the member 12, 45 and as the cage continues its downward course, its pressure on this curved portion turns the member 12 to the position shown in dotted lines in Fig. 3, thus turning the shaft 8, the knee 11 of which is thereby 50 turned from its position in front of the car wheel, into the position shown in dotted lines in Fig. 3, and in this position, the car is free to move forward on the cage.

In the operation of the combined trip and resetting weight shown in Figs. 5 and 6, the under surface of the descending cage floor contacts with the stud 19, and as the cage continues downwardly, the member 12 is turned to the position shown in Figs. 5 and 6, thus turning the shaft 8 to remove its knee 11 from the path of the car as heretofore explained.

In the use of either form of my device, when the cage again ascends, the weight 65 portion of either member 12, will return to

its normal vertical position, thereby again projecting the knee 11 into the path of a car to prevent it passing to the "sump."

As the downward movement of the cage is limited by the seat 7, which is omitted 70 from views 5 and 6, it will be seen that the cage cannot injure the shaft 8 by subjecting it to any force that cannot be taken up by the turning of the shaft. It will be noticed that with the construction illustrated in Figs. 5 and 6, the cage floor can descend below the level of shaft 8.

The member 12 may be formed integral with the shaft 8 as indicated in Fig. 4, or it may be formed separately and keyed to the 80 shaft as indicated in Figs. 3 and 6.

The bearings 9, adjacent the knee 11, are preferably located, as shown in the drawing, in close relation to the branches of the knee for the purpose of strengthening it.

The device may if desired be steadied in its car-stopping position, by having the gravitating force of the weight portion 14—17 bring the knee 11 against the side of the rail as shown in Fig. 3.

Although the detailed description of my device has been directed to its application to mining and tunneling operations, it is evident that it can be advantageously applied to various situations for the purpose of arresting the progress of a moving element, car or otherwise, towards a certain point.

Having thus described my invention, what I claim as new and desire to secure by Letters Patent thereon, is—

1. In a device of the character described, a rock-shaft having an outstanding object-arresting arm, and having a weight adapted to normally hold the rock-shaft in a determined position, and having also an element adapted to be actuated to rotate the shaft from its normal position.

2. In a device of the character described, a rock-shaft having an outstanding car-arresting arm, and having also a trip and weight the trip being adapted to be struck to turn the shaft from its normal position and the weight being adapted to return the shaft to its normal position.

3. In a device of the character described, a rock-shaft having a portion thereof bent to form an outstanding knee, and having also a combined trip and resetting weight the trip portion being adapted to be struck to turn the rock-shaft and the weight portion being adapted to return the shaft to its normal position.

4. In a device of the character described, a rock-shaft mounted adjacent a track the shaft having an outstanding arm adapted to normally project into the path of a car rolling on the track, the rock-shaft having also a trip and resetting weight the trip being adapted to be struck to turn the shaft for the purpose of turning its arm out of the path of the car.

the weight being adapted to return the arm to its normal position when the trip has been freed.

5. In a device of the character described, 5 the combination with a track, of bearings secured adjacent a rail thereof, a shaft mounted to turn in the bearings, the shaft having a portion bent outwardly to form a knee adapted to normally project into the path of 10 a car wheel traveling on the adjacent rail, the shaft having also at one end a head forming a combined trip and resetting weight, a cage adapted to move transversely of the shaft and track and adapted to receive 15 a car from the latter the cage being also adapted in traveling to its car-receiving position to strike the trip portion of the head

thereby turning the shaft and removing its knee from the path of car the weight portion of the head being adapted to return the shaft 20 and knee to its normal position when the cage retreats from its car-receiving position, means carried by the shaft contiguous to the bearings and adapted to maintain the shaft longitudinally therein, and means for limiting the movement of the cage transverse the shaft when the former is traveling to its car-receiving position.

In testimony whereof I affix my signature in presence of two witnesses.

GEORGE H. RICHARDS.
